UNITED STATES PATENT OFFICE

FRANK SANSONE, OF NEW ORLEANS, LOUISIANA

CUSHION HEEL

Application filed October 23, 1928. Serial No. 314,836.

Broadly, this invention relates to improvements in footwear and more particularly to a cushion heel for shoes, wherein the same provides means for the absorption of even more shock than can be realized in the use of the ordinary rubber heel, said means also serving to more equally distribute wear over the tread surface of the heel so that the usual uneven edge portion wear of the heel will not be occasioned when in use by even persons in the habit of placing the tread surface of their heels unevenly while walking.

An important object is to provide a heel of this character capable of being manufactured by substantially the same operations necessary in the production of the conventional rubber heel now in the general use.

Another object of importance resides in the provision of a cushion heel of integral construction, capable of being cheaply produced and wherein the parts thereof will not easily become separated through lack of poor assembly.

These and other objects of the invention will become apparent as the description of the invention is better understood.

In the drawings:—

Figure 1 represents a bottom view of the improved heel.

Fig. 2 is a top plan view of the heel.

Fig. 3 is a sectional view therethrough, taken substantially on the line 3—3 of Fig. 1, looking in the direction of the arrow, and

Fig. 4 is a transverse sectional view of the heel taken substantially on the line 4—4 of Fig. 1, and also looking in the direction of the arrow.

Referring to the drawings wherein like numerals designate like parts, a block of resilient material 1 such as rubber, is of the usual heel shape, and has embedded at its other end, adjacent the tread surface thereof, a plurality of washers arranged at spaced intervals adjacent the edge of the exterior.

A vertical opening 3 is formed in the block and is closed at its lower end by a tongue 4 projecting into the opening from the forward edge portion thereof. This tongue is toward its outer end bent to the edge portion of the opening, by a thin web 5. The tongue 4 and

the connecting web 5 are formed from the block 1 and are obviously of the same resilient material.

The tongue 4 is adapted to partially depend below the tread surface of the block 1 in substantially the manner shown in Fig. 3. The tongue 4 is formed adjacent its thick end with a recess in which a suitable anti-slipping insert 6, is disposed therein.

Thus, it will be seen that when the heel is in proper secured relation with a shoe, the tongue 4 partially depends below the tread surface of the heel while the same is not being engaged with the ground. In walking, as the heel is brought to rest on the ground, the tongue 4 will first engage the ground, and because of its resilient nature, suitable shock will be absorbed prior to the final resting of the tread surface of the heel upon the ground.

The bulkiness of the tongue 4 will be compensated for by the opening 3, so that the tread surface of the tongue 4 may become flush with the tread surface of the block 1, when the full weight of the person is brought to bear on the heel.

Having thus described my invention, what I claim as new is:—

A cushion heel comprising a heel block of the usual shape provided with a recess on its upper face and the lower portion of the said recess closed by a tongue-like member of substantially rigid material united to the heel block at its front edge portion and being flush with the lower surface of the heel block at this point, said tongue-like member having its rear portion normally disposed below the lower surface of the heel block and having its edge portion united to the heel block by a relatively thin flexible web.

In testimony whereof I affix my signature.

FRANK SANSONE.
